CLAIM

The ornamental design for a equipment mounting pad, as shown and described.

DESCRIPTION

FIG. 1 is a top isometric view of my new equipment mounting pad looking generally down toward the top surface thereof;

FIG. 2 is a top plan view thereof;

FIG. 3 is an end view taken generally from a position above FIG. 2 and looking down;

FIG. 4 is an end view taken generally from a position below FIG. 2 and looking up;

FIG. 5 is a side elevational view taken from a position to the left of FIG. 2, the opposite side being a mirror image; and, FIG. 6 is a bottom plan view of my new equipment mounting pad.
